US0D1094083S

(12) **United States Design Patent** (10) **Patent No.:** **US D1,094,083 S**
(45) **Date of Patent:** **** Sep. 23, 2025**

(54) **MAGNETIC DEVICE FOR AFFIXING
OBJECTS**

(71) Applicant: **Guangxian Li**, Yuanjiang (CN)

(72) Inventor: **Guangxian Li**, Yuanjiang (CN)

(**) Term: **15 Years**

(21) Appl. No.: **29/972,101**

(22) Filed: **Nov. 7, 2024**

(30) **Foreign Application Priority Data**

Jun. 28, 2024 (CN) 202430400445.3

(51) **LOC (15) Cl.** **08-08**

(74) *Attorney, Agent, or Firm* — Daniel M. Cohn;
Howard M. Cohn

(57) **CLAIM**

The ornamental design for a magnetic device for affixing objects as shown and described.

DESCRIPTION

FIG. 1 is a perspective view of a magnetic device for affixing objects showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an exploded perspective view of the magnetic device for affixing objects.

The dash-dash broken lines in the drawings depict portions of the magnetic device for affixing objects that form no part of the claimed design.

1 Claim, 9 Drawing Sheets
